(57) **CLAIM**

The ornamental design for a lip screening device, as shown and described.

DESCRIPTION

FIG. 1 is a front view of a lip screening device showing my new design;

FIG. 2 is a rear view of the lip screening device;

FIG. 3 is a left side view of the lip screening device;

FIG. 4 is a right side view of the lip screening device;

FIG. 5 is a top view of the lip screening device; and,

FIG. 6 is a bottom view of the lip screening device.

The broken lines illustrate portions of the lip screening device and form no part of the claimed design.
